RULE CLAMP

James E. Hastings, Athol, Mass., assignor to
 The L. S. Starrett Company, Athol, Mass., a
 corporation of Massachusetts

Application May 18, 1939, Serial No. 274,340

4 Claims. (Cl. 33—103)

Clamping devices for straight edges of various sorts have long been involved in the technique, as well as part of the equipment of the modern mechanic, but while developed in various styles 5 or types, they have all shown an annoying fault of wobbling or otherwise undesirably moving when in untightened positions. Because the clamp screw is normally untightened or slack when the user is trying to set up a straight 10 edge assembly for his work, any unexpected free or accidental movement, resulting in jiggling or wobbling of the screw shank with corresponding uncertain positioning of its foot, has caused a considerable amount of fumbling at critical moments. This usually occurs just at the very 15 time when it is most desired to secure a nicety and accuracy of relative disposition of the parts so as to obtain accurate reading of their graduations. It also has involved a loss of time on 20 the work or job at hand.

Various efforts have been made to overcome this difficulty, and while some corrective devices have been designed and tried, they have not been satisfactory from either standpoint of functioning in use or from the basis of cost of production. 25

It has been proposed to apply friction to the clamping stems or tightening nuts, but the suggested friction devices have usually been inconvenient of adjustment, or, when exposed so 30 as to be readily accessible, they have had the fault of catching on unrelated objects, or gathering dirt, to the vexation of the tidy mechanic and even to the lessened efficiency of the tool or instrument being used.

My concept is one capable of simple but efficient and inexpensive embodiments. These I have devised as blind or concealed members, but capable of ready adjustment of tension or friction. 35

As illustrative of my invention in some of its characteristic applications, I have shown several forms in the accompanying drawings which are not only satisfactory and practical for production and use, but are suggestive of other variants 40 which will doubtless occur to those skilled in these matters.

Throughout the specification and drawings like reference characters are employed to indicate corresponding parts, and in the drawings:

50 Fig. 1 shows a characteristic type of angled clamp attachment for straight edges according to my invention, with the scale members indicated as disposed at right angles to each other.

Fig. 2 is a partial vertical section on the line 55 2—2, of Fig. 1 through the threaded clamp hook.

Fig. 3 is a similar view on the indicated line 3—3, of Fig. 1.

Fig. 4 is a transverse section on the indicated line 4—4, of Fig. 1.

Fig. 5 is a detail of the friction piece of Figs. 5 1—4, inclusive.

Fig. 6 shows an angle clamp with a modified form of friction system, and partly sectioned to show one of the concealed assemblies.

Fig. 7 is a partial sectional view on the line 10 1—1, of Fig. 6.

Fig. 8 is a corresponding section on the line 8—8, of Fig. 6.

Fig. 9 shows an angle attachment with another 15 type of friction member for the clamp.

Fig. 10 is a section as indicated on the line 10—10, of Fig. 9.

Fig. 11 illustrates another type of clamp as 20 for rulers in alignment with the friction system of Figs. 1—4, inclusive, partly broken away to expose its concealment, and

Fig. 12 is a section on the line 12—12, of Fig. 11.

Referring to the angle head or attachment best illustrated in Figs. 1—4, inclusive, I provide 25 an angled head member 1 of usual and generally accepted type channelled at 1a to receive the usual blade B of a square or like instrument or tool with a groove b which is adapted to be engaged by the foot 2 of a screw clamping member lying in the internal transverse groove 1b. The screw threads of the member 3 are interrupted above the foot 2 to nearly its upper end so as to give a flat face 4 adapted to make clamping 30 contact with the blade B.

At its upper end as at 5 the stem of the clamp 35 3 is fully threaded to receive a knurled nut 6 having a depending cylindrical sleeve-like base 7 (Fig. 3). This base 7 which is adapted to enter the bearing portion 8 of the stem receiving aperture 9 which communicates with the groove 1b is circumferentially grooved or channelled as at 10. This groove 10 has a double function in that it provides a concealed friction bearing within the head 1 and also acts as a retainer for the 40 clamp assembly to support it from sagging vertically or wobbling out of the perpendicular.

In the embodiment of my invention shown in 45 Figs. 1—5, the groove 10 is engaged by a lateral shank 11' of a bent frictioning piece 11 preferably 50 of general U-shape. This frictioning piece 11 is of flat metal stock with a slight spring tension in its bow 11' so that its face 11' may come in contact with the adjacent wall of a longitudinal receiver or well 12 which intersects the transverse 55

groove $1b$. The shorter arm $11'$ of this frictioning piece fits into the circumferential groove 10 , the longer arm 11^4 being partially cut away so as to lie beneath the shoulder $8'$ of the bearing portion 8 of the nut 6 , the edge 11^5 bearing against the extreme top portion of the stem 5 of the clamp 3 and the extension $11a$ extending past the stem 5 further into the bottom of the well 12 .

The friction and holding piece 11 is pressed by a follower spring 13 , the tension of which is adjusted by a screw 14 tapped into the end of the aperture of the receiver 12 . As the screw 14 is exposed at the end of the head 1 it is perfectly easy for the mechanic to vary or adjust the tension or friction of the frictioning piece 11 on the upper end of the clamp 3 by turning up or slackening-off on the screw 14 which has a flat head end lying flush with the end of the head 1 so as to expose its slots $14'$ without itself protruding beyond the end face of the head.

This type of frictioning device 11 is particularly important in connection with the rule receiving clamp 16 which has a hook or foot 17 threaded as at 18 opposite its flat face 19 and fully threaded as at 25 at its upper end for receiving the knurled nut 21 . On the nut 21 is a depending sleeve 27 having circumferential groove 20 . The sleeve 27 is supported in a bearing 28 at the upper end of the threaded screwclamp aperture.

The clamp screw 16 had a usual half round bearing groove $16'$ in the head 1 which intersects the receiving channel 15 for a ruler R . These rulers may be of any type that the mechanic may happen to have in his kit, the edge r being drawn under an inclined shoulder having a slight bevel $15'$ for receiving rules, regardless of their thickness, and for drawing them inwardly against the rear wall of the rule receiving channel 15 .

The frictioning and receiving system of Figs. 1-5 inclusive is most important in the open sided rule receiving slot 15 as otherwise the threaded screw hook or clamp 16 would tend to dangle or wabble. It preferably is applied also to the blade engaging clamp 3 , although it is not as necessary because the blade B has a smooth sliding fit within the blade channel 9 of the head 1 . It does, however, also have its supporting function for the clamp 3 in the bearing of its portion 11^3 against the upper or outer wall of the groove 10 . This permits it to maintain the clamp 3 resiliently so that as the nut is turned to find the groove b in any width of blade B that may be employed, the clamp 3 may be axially moved against the slight resilience of the shank $11'$ to get the foot accurately aligned with the groove b . This frictioning system may also be used in other attachments or tools and more particularly as will in part be later specifically pointed out herein.

Referring to Figs. 6, 7 and 8, I have shown a modification in accordance with my invention in which the knurled head 31 has its depending sleeve or cylindrical portion 37 circumferentially grooved as at 30 to receive the blunt end of a combined friction piece and support 32 followed up by the tensioning spring 33 and adjustably backed up by the concealed screw 34 having its slotted head $34'$ exposed at the end of the frame 100 in general similarity to the system shown in Figs. 1-4. The depending sleeve 37 is supported in a cylindrical bearing 38 at the top of the aperture of the clamp screw 36 . The tension or friction on the threaded stem 36 may thus be readily varied or adjusted by the user without having to open up the interior parts.

As a further modification of my invention I have shown in Figs. 9 and 10 a frame 200 having a knurled nut 41 and depending interior sleeve portion 47 and grooved circumferentially as at 45 to receive the rounded end of the combined friction and supporting screw 44 having a slotted adjusting head $44'$.

In Figs. 11 and 12 I have shown my invention applied to a rule clamp 500 having its rule receiving undercut 515 open on one side and adapted to receive a pair of rulers or other straight edges end to end (not shown) to give the mechanic as long a combined straight edge as his available equipment will afford, by the use of this clamp.

As the rules or blades so clamped are a part of the equipment already in the tool box of the workman, he is provided with a long rule, even longer than his box will accommodate. The head portions of the rule clamps 500 are provided with the usual blade clamping hooks 56 footed as at 52 and screw threaded as at 55 to receive a nut 51 . This nut 51 has a depending cylindrical portion 57 in which is a groove 60 receiving friction piece 61 having an end $61'$ which is followed up by the blind screw 64 having a slotted head $64'$, one at each end of the head 500 , for adjustment.

The operation and function of the friction piece in such a clamp as 500 is much similar to that shown in Fig. 1 and needs no further description as its advantages will be readily familiar to those with shop usages and practices in setting up graduated straight edges or rules in end to end relation to get the maximum length of the user's tool box resources.

The modifications shown, as before suggested are not only illustrative and suggestive of other modifications and variants, but they represent simple and efficient forms well adapted to factory production at reasonable cost.

What I therefore claim and desire to secure by Letters Patent is:

1. In a clamp for straight edge blades, a frame, blade bearings on the frame, a blade clamp comprising a threaded stem, a clamping foot at the stem end, a clamp bearing in the frame and having a grooved bearing wall for guiding said stem, a nut threaded to said stem, a depending cylindrical base on the nut and having a peripheral retaining groove, said frame also having a bore radially intersecting said clamp bearing, a friction clip in said bore and having an arm lying in said peripheral groove, and a second arm in said bore extending inwardly of said intersection and groove within the frame exterior so as to be thereby concealed, a resilient follower for said clip, and an adjustable backing piece for said clip in said bore and threaded in its outer end to seal it externally of the frame.

2. A blade clamp, comprising a frame having a blade bearing and a clamp bearing, said clamp bearing terminating at its upper end in an enlarged recess, a threaded clamping stem in said clamp bearing and having a shoulder, a nut threaded on the upper end of said stem and having a depending reduced base seated in said recess, said frame also having a bore intersecting said recess, and a friction detent concealed in said bore and having a portion engaged with said nut base below the upper face of said frame to limit longitudinal movement of said stem in its bearing, and having another portion presenting a lateral edge engaged with the shoulder of said stem to hold said stem against rotation when the nut is turned on it.

3. The blade clamp of claim 2, said detent being U-shaped and having its bow disposed towards the outer end of said bore, and a resilient member in said bore acting upon the bowed portion of said detent.

4. A blade clamp, comprising a frame having a blade bearing and a clamp bearing, a threaded clamping stem in said clamp bearing having a shoulder between its ends and having blade engaging means at one end and having an operating

nut at its other end, said frame also having a bore intersecting said clamp bearing, and a friction clip concealed in said bore and having a portion engaged with said nut below the upper face of said frame to limit longitudinal movement of said stem in its bearing, and having another portion presenting a lateral edge engaged with the shoulder of said stem to hold said stem against rotation when the nut is turned on it.

5

JAMES E. HASTINGS. 10
